J. B. RHODES,
DISPENSING CAN.
APPLICATION FILED JUNE 2, 1921.

1,403,637.

Patented Jan. 17, 1922.

UNITED STATES PATENT OFFICE.

JAY B. RHODES, OF KALAMAZOO, MICHIGAN.

DISPENSING CAN.

1,403,637.

Specification of Letters Patent. Patented Jan. 17, 1922.

Application filed June 2, 1921. Serial No. 474,329.

To all whom it may concern:

Be it known that I, JAY B. RHODES, a citizen of the United States, residing at the city and county of Kalamazoo, State of Michigan, have invented certain new and useful Improvements in Dispensing Cans, of which the following is a specification.

This invention relates to improvements in dispensing cans.

10 My improved dispensing can is especially designed by me for the handling of lubricants such as in the sale of lubricants to motorists where the lubricant is poured into the crank case or lubricant receptacle of the engine.

The main objects of this invention are:

First: to provide an improved dispensing can by means of which the lubricant may be conveniently discharged into the crank case 20 of an engine or the like, at a rate permitting it to pass through the screened intake end without dripping on the floor or vehicle, and without soiling the hands of the person manipulating the same.

25 Second: to provide an improved dispensing can in which ordinary fruit jars of the "Mason" type may be used as a receptacle or container, and the original cartons in which the cans are shipped from the glass 30 factory utilized as cartons for shipping the complete dispensing cans.

Third: to provide an improved dispensing can which may be filled from a measuring pump without removing the cap.

35 Further objects, and objects relating to structural details, will definitely appear from the detailed description to follow.

I accomplish the objects of my invention by the devices and means described in the 40 following specification. The invention is clearly defined and pointed out in the claims.

A structure which is a preferred embodiment of my invention is clearly illustrated in the accompanying drawing, forming a 45 part of this application, in which:

Figure I is a perspective view of a carton or package containing the receptacles of my improved dispensing cans, the side of the carton being broken away to illustrate the 50 arrangement of the cans therein.

Figure II is a central section through the carton, containing the complete cans arranged for shipping.

Figure III is a front side elevation of one 55 of my improved dispensing cans.

Figure IV is an enlarged detail vertical

section on a line corresponding to line 4-4 of Figure III.

Figure V is an enlarged detail vertical section on a line corresponding with line 60 5-5 of Figure II, showing the arrangement of the parts when arranged for shipping.

In the drawings similar reference characters refer to similar parts throughout the several views, and the sectional views are 65 taken looking in the direction of the little arrows at the ends of the section lines.

Referring to the drawings, the measuring receptacles 1 are preferably of glass, the well-known "Mason" type of fruit jar being 70 very satisfactory. These cans are shipped from the glass factory in cartons 2, a dozen to a carton, the cartons being provided with outer closing caps 3 and inner closing caps 4. The cartons are usually formed of celluloid board.

I provide a cap 5 preferably dome shaped as illustrated, the cap having an outwardly projecting flange 6 at its lower end adapted to overlap the end 7 of the neck 8 of the receptacle. A gasket 9 is disposed between the flange 6 and the edge of the receptacle neck. The collar 10 is threaded upon the neck and is provided with an inturned flange, which engages the flange of the cap, thereby providing a secure joint between the cap and the can. The gasket also protects the edge of the can neck so that it is not likely to be chipped by metal coming in contact with the glass. The cap is provided with a central 90 spout 12, of such dimensions as to permit the filling of the receptacle through the spout as by means of a measuring pump, it being usual in the dispensing of lubricants to motorists to measure the lubricant by 95 means of a measuring pump.

I provide a vent tube 13 which is arranged at the front of the spout and so that it may be fingered; that is, the finger placed over the spout to control the discharge from 100 the spout. The upper end of the vent tube is preferably beveled as illustrated to facilitate fingering. The lower end of the vent tube is arranged so that when the receptacle is filled to its normal capacity the end of 105 the tube is above the liquid level and the tube is also arranged so that in filling through the spout the lubricator does not come in contact with the vent, the lower end of the vent tube being beveled away from the spout 110 as shown in Figure IV.

The diameter of the cap is such that it

may be inverted within the can, and the collar thereof threaded thereon, thereby retaining the parts in assembled relation for shipment or storage. When thus arranged 5 the dispensing cans may be placed in the cartons 2 for shipment, thus, for reshipment utilizing the same cartons in which the cans are received from the glass factory. This also provides a very compact package.

10 By arranging the parts in this manner the lubricant is introduced into the receptacle through the spout, which avoids the necessity of removing the cap and its discharge may be accurately controlled, making it possible 15 to handle lubricants without dripping on the vehicle or floor or soiling the hands of the operator.

Where it is necessary to remove the cap in order to introduce the lubricant to the receptacle it is found quite impossible to avoid smearing the outer part of the receptacle in removing the cap or replacing it.

Further, an affective joint between the cap and the receptacle cannot be maintained in 25 handling lubricants where the cap is repeatedly removed. In the applicant's structure the gasket is arranged so that it is supported within the clamping collar and retained in place even when the same is coated 30 with lubricant, or when deteriorated by contact with the lubricator.

Having thus described my invention, what I claim as new, and desire to secure by Letters Patent, is:

35 1. A dispensing can comprising a receptacle having a threaded neck, a dome shaped cap having an outwardly projecting flange at its bottom overlapping the end of the neck and a discharge and filling spout at the 40 top thereof of such diameter as to permit filling as well as discharging of the receptacle therethrough, the diameter of the cap being such that it may be inverted within the neck of the receptacle with its flange 45 overlapping the end thereof, a gasket arranged between the end of the neck and the flange of said cap, a collar threaded upon said receptacle to engage the flange of said cap, and a vent tube depending into said 50 front side of the spout.

2. A dispensing can comprising a receptacle having a threaded neck, a dome shaped cap having an outwardly projecting flange at its bottom overlapping the end of the neck and a discharge end filling spout at the 55 top thereof of such diameter as to permit filling as well as discharging of the receptacle therethrough, a gasket arranged between the end of the neck and the flange of 60 said cap, a collar threaded upon said receptacle to engage the flange of said cap, and a vent tube depending into said cap at the front side of the spout.

3. A dispensing can comprising a receptacle having a threaded neck, a dome shaped

cap having an outwardly projecting flange at its bottom overlapping the end of the neck and a discharge and filling spout at the top thereof of such diameter as to permit filling as well as discharging of the receptacle therethrough, a gasket arranged between the end of the neck and the flange of said cap, a collar threaded upon said receptacle to engage the flange of said cap, and a vent tube depending into said cap at the 70 front side of the spout with its lower end above the level of the liquid when filled to its normal capacity and beveled away from the spout so that the liquid does not come into contact with the vent tube in filling the 80 receptacle through the spout, the upper end of the tube being beveled to facilitate fingering to control the passage of air therethrough.

4. A dispensing can comprising a receptacle having a threaded neck, a cap having an outwardly projecting flange at its bottom overlapping the end of the neck and a discharge and filling spout of such diameter as to permit filling as well as discharging of 90 the receptacle therethrough, the diameter of the cap being such that it may be inverted within the neck of the receptacle with its flange overlapping the end thereof, a gasket arranged between the end of the neck and the flange of said cap, a collar threaded upon said receptacle to engage the flange of said cap, and a vent tube depending into said cap with its lower end above the normal liquid level of the receptacle. 100

5. A dispensing can comprising a receptacle, a dome-shaped cap having a discharge and a filling spout at the top thereof of such diameter as to permit filling as well as discharging of the receptacle therethrough, and a vent tube depending into said cap at the front side of the spout with its lower end above the normal liquid level of the receptacle and positioned out of alignment with the spout and so that the liquid does 105 not come into contact with its inner end in filling the receptacle through the spout, the upper end of the vent tube being positioned to permit fingering to control the passage of air therethrough. 110

6. A dispensing can comprising a receptacle, a cap therefor having a discharge and filling spout of such diameter as to permit filling as well as discharging of the receptacle therethrough, and a vent tube depending into said cap and disposed so that the liquid does not cover the lower end of the same when the receptacle is filled to its normal capacity, the inner end of said vent tube being positioned so that the liquid does 115 not come into contact with the vent tube in filling the receptacle through the spout. 120

In witness whereof, I have hereunto set my hand and seal.

JAY B. RHODES. [L.S.]
